UNITED STATES PATENT OFFICE.

HENRY BRUNELLE, OF WARE, MASSACHUSETTS.

PICKER-STICK CHECK.

1,070,768.

Specification of Letters Patent. Patented Aug. 19, 1913.

Application filed May 12, 1913. Serial No. 767,037.

To all whom it may concern:

Be it known that I, HENRY BRUNELLE, a citizen of the United States of America, and resident of Ware, in the county of 5 Hampden and State of Massachusetts, have invented certain new and useful Improvements in Picker-Stick Checks, of which the following is a full, clear, and exact description.

10 The object of this invention is to provide a check device with which the picker stick coacts upon its retiring movement which is especially well adapted to fulfil the purposes for which such devices are designed 15 for cushioning the picker and minimizing the destructive effect thereon of the shuttle in its motion toward and against the picker.

15 The invention is described in conjunction with the accompanying drawings and is set 20 forth in the claims.

In the drawings:—Figure 1 is a side elevation showing the picker check as mounted on and carried by the rocking support for the lay and in its relation to the picker 25 stick a portion of which and some of its appurtenances are shown. Fig. 2 is a side elevation; Fig. 3 a vertical elevation or edge view, and Fig. 4 a plan view of the picker check itself and as removed from the support in the loom therefor; Fig. 5 is a horizontal sectional view through a pivotally jointed part of the device as taken on the line 5—5, Fig. 3.

Similar characters of reference indicate 35 corresponding parts in all of the views.

In the drawings, 10 represents the rock-shaft on which the lay (not shown) is carried and by which the picker stick 12 is also carried, the same being secured to the rocker 40 13 which acts in the usual way relatively to the flat topped extension 14 of the rock-shaft,—15 representing a portion of the strap by which the picker is forcibly thrust or swung for its shuttle impelling movement, and 15 representing a spring including retiring device for the picker, these parts being assumed to be as usual in looms of the most common type and of most extensive use.

50 Now as regards the picker stick check which as will be perceived is an attachment to be secured to and carried as a part of the rocking support for the lay, A represents a bracket adapted to be rigidly secured on the 55 lay support as by having at the lower portion thereof a recessed lug or confining mem-

ber *a* which matches with and by a bolt is secured to a suitable lug formed as a depending part of the aforementioned flat topped extension of the lay carrying rockshaft. 60 This bracket at its rear side and near its attachment portion *a* is made with a shoulder *b*.

The bracket is formed with an upwardly and outwardly extended portion *d*, offset 65 from the plane of which is the aforementioned shoulder *b* which shoulder, or abutment is formed as a top wall of the attachment member.

Near the outer extremity of the portion *d* 70 of the bracket A is a slot *f* horizontally extending from a rearward to a forward direction relatively to the line or plane of swinging movement of the picker stick.

B represents an angular lever having a 75 transverse hole *g* through its elbow portion *e* as represented in Fig. 5, and a bolt *h* or other appropriate pivot forming member is passed through the said hole *g* in the lever and through said slot *f* and has combined 80 therewith means whereby such bolt may be confined on said bracket at any place in the length of the slot. Said lever comprises, as an extension from its elbow an upstanding arm *i* having a transverse lug or abutment 85 *j* to be engaged by the picker stick in the retractile movement thereof; and said lever also comprises an arm *m* here represented as curved, extending horizontally and then downwardly and adapted to have a motion-limiting engagement with the shoulder *b* 90 formed as a part of the bracket.

k represents a retractive spring applied to the said elbow lever B for maintaining the upstanding arm in a normal forward or inward position, and as limited by the engagement of the other arm *m* with the shoulder *b*. The curved arm *m* has an upwardly and rearwardly extended lug *o* and the lower portion of the bracket has a rearwardly extended lug *p* at quite a distance below the one *o* to which lugs the eye formed ends of the aforesaid mentioned spring *k* are attached,—all in such manner that the spring will be stretched when the lever-like picker 100 check member is swung outwardly from its normal position, in which latter position the spring tends to maintain it.

As a special and entirely practical and satisfactory means for effecting the adjustment of the check lever pivot lengthwise of the slot *f*, and for the confinement of the 110

parts in adjusted position, the hole through the elbow of the check lever is comparatively large, the same receiving therethrough an annular bushing *s* having a flange *t* at its 5 end adjacent the rear face of the bracket portion *d*.

The length of the bushing in a direction rearwardly from said flange is slightly greater than the distance transversely 10 through the lever elbow which portion of the latter for sufficient length of the bearing is made with the extension hub *u*.

A washer *v* overlies the outer face of the bracket across the slot; and the bolt *h*, the 15 head of which is in engagement with the washer *v* passes through the slot and through the bushing and receives at its end opposite the head the binding nut *w* which through the medium of the washer exerts its confining 20 action for the bolt against the end of the bushing effectively holding such bushing in confinement in whatever position along the slot it may be adjusted, but in no way tending to bind or impede the freest 25 possible swinging movement of the check lever on the bushing which is sleeved over the bolt.

As manifest, the check lever may be 30 bodily adjusted inwardly or outwardly relatively to the bracket so as to be positioned for its most advantageous checking of the picker; and such check lever is thereby most properly conditioned as a factor for the cushioning of the picker stick which is required to withstand the many time repeated 35 impacts of the loom shuttle.

I claim:—

1. In a picker stick check, the combination with a bracket adapted to be mounted on the 40 support for the lay comprising a shouldered attachment portion and a rearwardly and upwardly extended lever-supporting member located in a plane offset from said shoulder forming attachment member, having a

slot extending in a rearward to a forward 45 direction, of an angular lever having a transverse hole therethrough at its elbow portion, and a pivot member passed through said perforation and said slot and having means appurtenant thereto whereby it may be confined 50 on said bracket at any place in the length of said slot, said lever comprising an upstanding arm having an abutment to be engaged by the picker stick in its retiring movement and an arm adapted to have 55 a motion-limiting engagement with the shoulder of the attachment part of said bracket, and a retractive spring applied to said elbow lever for maintaining the upstanding arm in a normal, forward, position 60 as limited by the engagement of the other arm with the said shoulder.

2. In a picker stick check, the combination with a bracket adapted to be mounted on the support for the lay and having an 65 angularly extended lug, of an angular lever, pivotally mounted on said bracket, comprising an upstanding arm having an abutment to be engaged by the picker stick in its retiring movement and an arm adapted to 70 have a motion-limiting engagement with a part of said bracket, said arm having an angularly extending lug, a retractive spring between and secured to said lugs and operative to maintain the upstanding arm in a 75 normal, forward position as limited by the engagement of the other arm with the said bracket, the said angular lever being forwardly and rearwardly adjustable on the bracket, and means for confining such lever 80 in adjusted position.

Signed by me at Springfield, Mass., in presence of two subscribing witnesses.

HENRY BRUNELLE.
